DEVICE FOR DARNING PURPOSES

Dusinus Peder Christensen, Aalborg, Denmark

Application December 22, 1947, Serial No. 793,172
In Denmark December 23, 1946

6 Claims. (Cl. 139—33.5)

1

A device for the darning of holes of cloth is known. This device has a series of revolving needles, round which the thread, which is drawn in one direction of the hole, is placed in such a manner that each needle has two threads parallel to each other which by the turning of the needle alternately are brought to lie in the top position, so that the cross threads can easily be carried in between the above mentioned longitudinal threads. This device involves the inconvenience that one end of the darning formed is not connected with the material being darned, so that this end must be fastened by sewing afterwards. Furthermore, it involves the inconvenience that the placing of the device takes a rather long time, as part of it is to be placed in the subject which is to be darned, after which another part is to be placed on the outside and connected with the first part by means of an elastic band.

These inconveniences have been avoided with the present invention, which relates to a device for darning purposes, thereby that the longitudinal threads are not bent round the needles, but drawn beside these, so that they come in under a hook of the needles, by means of which every second thread can be lowered and raised alternately, so that the cross threads can be carried in between the longitudinal threads.

Further, a device is known, in which two combs are movably arranged beside each other in a slit in a head for the supporting of the longitudinal threads for darning. This device can, however, only be used for darning coarser materials, not for such things as silk stockings, as the teeth of the movable combs which are not in operation during the work—which is the case when smaller holes are darned—at the upwards and downwards movement damage the stocking by their pressure outside the hole.

This inconvenience has been avoided with the present invention, as the upward and downward movable needles are only pulled downwards during the work.

Furthermore, the darning cannot be finished with the known device, as the combs are beside each other and thus prevent the carrying through of the last cross threads.

This disadvantage has also been avoided with the device according the invention by having only one row of needles.

The characteristic feature of the invention is that a row of needles is fixed in the slit of the head, every second of which is fixed to one plate, and every second to another plate, which plates are situated one above the other in a space of the head and are individually movable downwards and upwards. To either of the plates is fixed a band of elastic material, which is fixed to a rail of the handle of the device, against which band a push button presses, which is mov-

2

ably arranged in the handle, while in the top of the handle pins or rolls are arranged, which support the bands. As an alternative embodiment the plates in which the needles are fixed are arranged adjacent each other in the head, each fixed to a movable rod, which is guided in the handle and has on its side a pin whereby a sloping face of a push button can influence the rod to a downward motion.

10 In the drawing shown

Fig. 1 a vertical longitudinal section of a device according to the invention,

Fig. 2 is a section taken on the line 2—2 in Fig. 1,

15 Fig. 3 is a section taken on the line 3—3 in Fig. 1,

Fig. 4 is a section taken on the line 4—4 in Fig. 1,

Fig. 5 is a detail,

20 Fig. 6 is a vertical longitudinal section of another form of construction of the invention,

Fig. 7 is a section taken on the line 7—7 in Fig. 6 and

Fig. 8 is a detail.

The device consists of a dish-shaped head 1 with a handle 2. The head has a channel 3, into which three plates, 4, 5 and 6, are inserted, one above the other. The plate 5 is stationary

25 in the channel 3, whereas the plates or supporting bars 4 and 6 are movable upwards and downwards in the channel. To the plate 4 are fixed a number of needles 7, and to the plate 6 are fixed a further number of needles 8. The needles 8 pass loosely upwards through some holes in the plates 5 and 4.

30 To the underside of the plate 4 there is fixed a band 9 of elastic material and this band 9 is further fixed to a rail 10 at the bottom end of the handle 2. The band passes loosely through holes in the plates 5 and 6 and

35 is supported by a pin or roll 11 fixed at the top end of the handle 2. To the underside of the plate 6 is fixed another band 12, which at its foot is also fixed to the rail 10. The band 12 is supported by a pin or roll 13 arranged at the top-end of the handle. In handle 2 push buttons

40 14 and 15 are movably arranged to press against the band 9 and the band 12 respectively. Between the plates 4 and 5 a spring 16 is arranged at each end of the plates, under the influence

45 of which the plate 4 is kept raised. Between the plate 6 and the bottom of the channel 3 a spring 17 is arranged at each end, which keeps the plate 6 raised. Thus the supporting bars 4 and 6 are biased to urge them in positions to

50 normally expose and extend the needles 7 and 8 from the hollow head 1. At the top the channel 3 is covered with a plate 18 having a narrow slit 19, into which the needles can be drawn down.

55 In use the material which is to be darned is placed on the top of the head 1 and fixed to the device by means of an elastic band in a groove

60

20 of the head 1. By means of a darning needle longitudinal threads are placed over the hole of the material in such a manner that the longitudinal threads are stitched into the material at either end of the hole. During the drawing of the longitudinal threads these are carried in under a hook of the needles 7 and 8. When the longitudinal threads have been drawn, the push button 14 is pressed, whereby the band 9 will be curved, and the latter will pull the plate 4 with the needles 7 downwards, so that every second longitudinal thread is pulled downwards, by which an opening is formed between the longitudinal threads. By means of the darning needle a cross thread is carried through the opening, after which the push button 14 is released, and the push button 15 is pressed, whereby the plate 6 with the needles 8 is pulled downwards, so that an opening between every second thread is again formed. When all the cross threads have been drawn, the hooks of the needles are drawn out by pulling the material a little sideways.

In the form of construction of the invention shown in Figs. 6-8 the plates, in which the needles are fixed, are arranged adjacent each other instead of one above the other. These plates or rods are 21 and 22 respectively, either of which is fixed to a rod 23, which is movably arranged in the cross piece 24 of the handle 2. Each of the rods 23 has at its side a pin 25, against which a sloping face 26 of a push button 27, movably arranged in the side of the handle 2, presses. The rods 23 together with the needle plates 21 and 22 are kept raised under the influence of springs 28. The needle plates move downwards and upwards in a slit 29 of the head 1, and each of the plates 21 and 22 has a row of Z-shaped needles 30 and 31 respectively, which are guided between two rails 32. Off each of the needles there is a groove 33, in which the rods are covered, when they are pulled down between the rails 32 of the needles. The needle, by means of which the cross threads are carried between the longitudinal threads, is guided between the side of the needles 30 and 31, which are not pulled down, and one of the rails 32. The alternate pulling down of the needles is effected by pressing one or the other of the push buttons 27.

The grooves 33 serve to take up the thread drawn down by the needle, in order to render a larger interspace between the raised and the lowered threads, which will facilitate the carrying of the cross threads through the interspace.

When a device according to this form of construction is to be used it is applied to the fabric to be darned, after which the longitudinal threads are drawn as described above. Then one of the push buttons 27 is pressed by which all the needles 30 are pulled downwards, thereby pulling every second of the longitudinal threads downwards, so that the needle with the cross thread can be carried in between these and the threads of the needles 31, which are in their top position. When the cross thread is carried through, the push button 27 is released, and the other push button 27 is pressed, by which the needles 31 with their threads are pulled downwards.

I claim:

1. A device for darning and repairing woven fabrics comprising a head member provided with a handle member, said head member having a hollow portion therein, a pair of supporting bars each provided with a row of needles, said sup-

porting bars being movably mounted in the hollow portion in the head member and being biased to urge them in positions to normally expose and extend the needles from the hollow portion in the head, and means in the handle member to actuate the supporting bars to draw the needles into the hollow portion in the head against the biasing action.

2. A device for darning and repairing woven fabrics comprising a head member provided with a handle member, said head member having a hollow portion therein, a pair of supporting bars each provided with a row of needles, said supporting bars being movably mounted in the hollow portion in the head member and being biased to urge them in positions to normally expose and extend the needles from the hollow portion in the head, a rod fixed to each supporting bar, and means in the handle to actuate the rod to draw the needles into the hollow portion in the head against the biasing action.

3. A device for darning and repairing woven fabrics comprising a head member provided with a handle member, said head member having a hollow portion therein, a pair of supporting bars each provided with a row of needles, said supporting bars being movably mounted in the hollow portion in the head member and being biased to urge them in positions to normally expose and extend the needles from the hollow portion in the head, a rod fixed to each supporting bar and a push button in the handle for each supporting bar to bend the rod and thereby draw the needles into the hollow portion in the head against the biasing action.

4. A device for darning and repairing woven fabrics comprising a head member provided with a handle member, said head member having a hollow portion therein, a pair of supporting bars each provided with a row of needles, said supporting bars being movably mounted in the hollow portion in the head member and being biased to urge them in positions to normally expose and extend the needles from the hollow portion in the head, a rod fixed to each supporting bar, and a cam member in the handle for each supporting bar to force the rod longitudinally in the handle member and thereby draw the needles into the hollow portion in the head against the biasing action.

5. A device according to claim 1, in which the supporting bars are arranged one above the other with the needles for the lower bar projecting through the upper supporting bar.

55 6. A device according to claim 1, in which the supporting bars are arranged adjacent each other with the means in the handle member being in the form of a rod secured to each bar and a cam to actuate each rod.
